APPARATUS FOR RECEIVING BALLS OR ROLLS OF SLIVER DISCHARGED FROM A SLIVER BALLING MACHINE

Application filed June 4, 1931, Serial No. 542,170, and in Great Britain June 4, 1930.

The subject of this invention is an automatic sliver roll receiver adapted for use in conjunction with a sliver balling machine and serving to receive the rolls or balls ejected from the balling machine.

The roll receiver according to the invention is so contrived that each roll ejected from the balling machine, when deposited on the receiver, is displaced axially to vacate the roll-receiving station and in such displacement to impart endwise movement to a series of rolls already received, so that the foremost roll of the series is brought to a position where it may be conveniently picked up or is delivered from the receiver on to the floor. Or there may be provided in series with the receiver which receives sliver from a balling machine fitted as an adjunct to a card a transfer device serving to transfer the balls or rolls of sliver to a drawing frame, for example, the balls or rolls being transferred manually or automatically from the receiver to the transfer device.

Thus there may be disposed between a pair of cards a pair of inclined chutes the high end of each of which terminates adjacent to the relative sliver receiver and the low end of which terminates beyond the front of the relative card, the arrangement being such that, as the rolls are ejected from the receiver, they are lifted manually or mechanically on to the chute down which they roll towards the drawing frame.

Each chute may serve as a magazine, in which case the rolls will be allowed to bank up thereon and move forwardly together as each front roll is removed from the low end of the chute.

As is understood, the rolls or balls are so wound that they do not unwind while rolling down the respective chutes.

In the accompanying drawing Figs. 1 and 2 are part elevations and part sections at right angles to one another of an automatic sliver roll receiver constructed in accordance with the invention.

Referring to the drawing, the sliver roll receiver shown is so contrived that each roll 1 ejected from the balling machine (not shown), when deposited on the receiver, is

displaced axially in the direction indicated by the arrow A (Fig. 1) to vacate the roll-receiving station indicated at 2 and in such displacement to impart endwise movement to a series of rolls already received, so that the foremost roll 1' of the series is brought to a position where it may be conveniently picked up or is delivered from the receiver on to the floor. The receiver includes spaced parallel guide members 3, 3' and 3² extending in a direction parallel to the axis of the roll which rolls down an inclined chute 4 to the receiving station 2, and a movable carriage 5 arranged between the guide member 3 and the guide members 3', 3² and adapted to be automatically set in action by the ejected roll 1 to impart axial movement thereto and to be returned automatically to position after displacement of the roll. As each roll 1 arrives at the receiving station 2 from the balling machine it sets pawl-and-rack mechanism into operation to effect stepwise advance movement of the carriage 5 and therewith of the roll 1. The guide member 3 is constituted by a fixed bar and the guide members 3', 3² are constituted, respectively, by a fixed plate and by a movable plate which is adapted to be moved by the ejected roll and which is operatively connected to a reciprocating pawl-bar 7 provided with advance and reverse pawls 8, 9 engageable, respectively, with advance and reverse racks 10, 11 carried by the carriage 5.

When the ejected roll 1 arrives at the receiving station 2 it is sustained between the guide members 3, 3², movement of the member 3² being accompanied by lateral shift of the pawl-bar 7 to bring about engagement of the advance pawl 8 with its rack 10 as shown best in Fig. 2.

The pawl-bar 7 is reciprocated by mechanism including a bell-crank lever 12, 12² crank-actuated from the main shaft 13 of the balling machine.

While the receiver awaits reception of a roll the reverse pawl 9 reciprocates idly over an untoothed portion 14 at one end of the reverse rack 11 and the advance pawl 8 reciprocates idly in a space 15 between the racks 10, 11.

90

95

100

The carriage 5 is provided with an up-standing bracket 16 engageable with the roll 1 whereby to propel the series of rolls sustained by the guide members 3, 3' which are made of sufficient length to carry say four or five rolls.

The movable guide plate 3² is carried by one arm 17 of a bell-crank lever 17, 18 fulcrumed at 19 and influenced by a tension spring 20 so that an adjustable screw-stop 21 carried by the arm 18 is maintained normally in engagement with an abutment 22. 10 26 denotes an adjustable screw-stop engageable by the arm 17 whereby to limit outward movement of said arm under the weight of the roll 1. Pivottally connected at 23 to the arm 17 is one end of a link 24 of which the other end is pivottally connected at 25 to one end of the pawl-bar 7 the other end of which 20 is pivottally connected at 12² to the arm 12² of the bell-crank lever 12, 12². The carriage 5 is mounted on a base 5' slidably engaging guides 27 mounted on the bed-plate 28 of the receiver.

25 T (Fig. 1) denotes the stroke of the carriage 5, said distance T being the sum of:— a distance T' travelled by the carriage before the roll 1 engages the roll 1 ejected from the balling machine, a distance T² equal to 30 the width of the roll, and a distance T³ representing the distance travelled by the roll 1 in the advance of the carriage before the roll 1 abuts on the first roll of the series of rolls 35 already on the receiver. It will thus be understood that, with the reception of each roll by the receiver, there is imparted to the series of rolls already thereon an axial displacement equal to the width of one roll, i. e., 40 an axial displacement equal to the distance T².

As will readily be understood, when the ejected roll 1 engages the guide plate 3² the lever 17, 18 is rocked on its fulcrum 19 in the direction indicated by the arrow C (Fig. 45 2) until the arm 17 abuts on the stop-screw 26. The movement of the arm 17 effects through the medium of the link 24 lateral shift of the pawl-bar 7 to bring about advance 50 operation of the carriage 5 as hereinbefore explained. At the end of the forward travel of the carriage 5, i. e., when the trailing face of the roll 1 reaches the point B, the roll overruns the guide plate 3² on to the guide 55 plate 3' whereby the guide plate 3² and the lever 17, 18 are relieved of load, release of the lever 17, 18 being followed by its return to normal position under the action of the spring 20 and lateral shift of the pawl-bar 60 7 whereby the advance pawl 8 is disengaged from its rack 10 and the reverse pawl 9 is moved into engagement with its rack 11 to effect reverse movement of the carriage 5 to normal position as indicated in Fig. 1, ready 65 for reception of the next roll.

What we claim is:—

1. A sliver roll receiver for the purpose specified, comprising, in combination, members for guiding the sliver rolls from a receiving station to a delivery point, one of said members being movable under the influence of the weight of a roll, a carriage movable in the general direction of said members, advance and return racks connected to said carriage, a reciprocatory pawl engageable with 70 said advance rack, connections between said movable guiding member and said pawl whereby the weight of a roll acting on said movable guiding member establishes operative relation between said pawl and said advance rack, a reciprocatory return pawl, and means tending to establish operative relation between said return pawl and said return rack, said last mentioned means being effective when the weight of the roll ceases to act 75 on said movable guide member. 80

2. A sliver roll receiver for the purpose specified, comprising, in combination, members for guiding the sliver rolls from a receiving station to a delivery point, one of said members being movable under the influence of the weight of a roll, a carriage movable in the general direction of said members, advance and return racks connected to said carriage, a pawl engageable with said advance 90 rack, a pawl engageable with said return rack, a reciprocatory bar carrying said pawls and shiftable transversely of said racks, connections between said movable guiding member and said bar whereby the weight of a roll acting on said movable guiding member shifts said bar to establish operative relation between said first mentioned pawl and said advance rack, and automatic means for shifting said bar in the direction to establish operative relation between said second mentioned pawl and said return rack. 100

3. A sliver roll receiver for the purpose specified, comprising, in combination, members for guiding the sliver rolls from a receiving station to a delivery point, one of said members being movable under the influence of the weight of a roll, a carriage movable in the general direction of said members, advance and return racks connected to 110 said carriage, a reciprocatory pawl engageable with said advance rack, connections between said movable guiding member and said pawl whereby the weight of a roll acting on said movable guiding member establishes operative relation between said pawl and said advance rack to cause said carriage to be propelled in the direction away from said receiving station, a reciprocatory return pawl, and spring means acting on said movable 115 guide member and operative to establish operative relation between said return pawl and said return rack when the roll previously acting on said movable guide member is propelled beyond said guiding member. 120

4. A sliver roll receiver for the purpose specified, comprising, in combination, members for guiding the sliver rolls from a receiving station to a delivery point, one of
5 said members being movable under the influence of the weight of a roll, a carriage movable in the general direction of said members, advance and return racks connected to said carriage, a pawl engageable with said advance rack, a pawl engageable with said return rack, a reciprocatory bar carrying said pawls and shiftable transversely of said racks, a lever carrying said movable guiding member and linked to said bar, a spring acting on said lever to oppose rocking movement of the lever under the influence of the weight of a roll acting on said movable guide member, and adjustable stops for limiting rocking movement of said lever.
- 20 5. A sliver roll receiver for the purpose specified, comprising, in combination, members for guiding the sliver rolls from a receiving station to a delivery point, one of said members being movable under the influence of the weight of a roll, a carriage movable in the direction of the axes of the rolls, means effective on depression of said movable guide member by a roll to propel said carriage in the direction away from said 25 receiving station, and means effective on relief of said movable guide member from the weight of a roll for returning said carriage.
- 30 In testimony whereof we have signed our names to this specification.
